US00D805573S

(12) **United States Design Patent** (10) **Patent No.:** **US D805,573 S**
Xia (45) **Date of Patent:** **** Dec. 19, 2017**

(54) **MAGNETIC MOUNT FOR ELECTRONIC DEVICE**

(71) Applicant: **Shenzhen Shixian Security Technology Co., Ltd.**, Shenzhen (CN)

(72) Inventor: **Hongxing Xia**, Shenzhen (CN)

(**) Term: **15 Years**

(21) Appl. No.: **29/561,686**

(22) Filed: **Apr. 19, 2016**

(51) **LOC (10) Cl.** **16-05**

(52) **U.S. Cl.**

USPC **D16/219**

(58) **Field of Classification Search**

(57) **CLAIM**

The ornamental design for a magnetic mount for electronic device, as shown and described.

DESCRIPTION

FIG. 1 is a front, left perspective view of a magnetic mount for electronic device showing my new design;

FIG. 2 is a rear, left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the magnetic mount for electronic device that form no part of the claimed design.

1 Claim, 8 Drawing Sheets
